UNITED STATES PATENT OFFICE.

EDWARD E. CLEMENT, OF WASHINGTON, DISTRICT OF COLUMBIA, ASSIGNOR TO
EDWARD F. COLLADAY, OF WASHINGTON, DISTRICT OF COLUMBIA.

RADIO RECEIVING INSTRUMENT FOR SYSTEMS OF BROADCAST DISTRIBUTION.

Application filed November 25, 1925. Serial No. 71,454.

My invention relates to subscriber's station circuits and apparatus for combined telephone and radio telephone systems in which current is supplied to the radio telephones as well as the telephones over a common system of wired lines. It has for its object to render the supply of energy to the subscriber's radio telephone constant whether his telephone is in use or not. The present application is a continuation in part of my copending application, Serial No. 720,870, filed June 18, 1924, and is also in the nature of an improvement over the invention described and claimed in my prior copending applications Serial No. 581,829, filed August 14, 1922, Patent No. 1,522,357, patented January 6, 1925, and Serial No. 699,023, filed March 13, 1924. Where the usual centralized battery is employed in a telephone system, a constant potential is maintained on the lines, and when the telephones are not in use, the radio telephones can be adjusted so as to function properly on the telephone current, using the metallic circuit only, without substation grounds; but it is desirable to compensate for the change in potential when a telephone transmitter of low resistance is bridged across the line, especially with respect to the filament current taken over that line. As disclosed in one of the applications referred to, a cut off relay is provided at the subscriber's station, which becomes energized when the telephone is in use, to disconnect the normal charging circuit from the line to the radio telephone storage battery. In another application a bridged arrangement of both instruments is resorted to, the plate and filament circuits being parallel, with resistance interposed in the filament circuit. In the present case I employ a combination of the principles thus disclosed, using bridging circuits without grounds, and both compensating resistance and a booster battery which will automatically regulate the voltage and the current in the filament circuit when the telephone is in use.

A secondary object of the invention is to combine the circuits of the telephone and radio telephone at a subscriber's station so that the radio messages may be received on the ordinary telephone receiver or on a special receiver attached to the telephone set, the combined instrument thus becoming an exten-

sion telephone with radio receiving attachment.

A third object of the invention is to provide means whereby the telephone hook switch may be disabled or mechanically locked while the telephone receiver is being used for radio receiving, and therefore off the hook.

Other objects will sufficiently appear from the detailed description hereinafter.

My invention is illustrated in the accompanying drawings, in which—

Fig. 1 is a diagram showing a subscriber's station provided with a floating booster battery, and a cut off relay energized when the telephone goes into service, to disconnect the radio telephone and its battery from the line.

Fig. 2 shows a similar arrangement of a booster battery, but with the cut off contacts of the radio telephone operated by the telephone switchhook.

Fig. 3 shows a similar arrangement of a booster battery permanently connected to the telephone line terminals through choke coils to prevent leakage of telephone currents through the booster battery, as well as to regulate the flow of current from the booster into the telephone circuit.

Fig. 4 shows in skeleton outline the method of connecting a common booster battery to a number of lines.

Fig. 5 is a diagram similar to Fig. 1, showing an electrical connection from the radio telephone set to the telephone receiver of the ordinary telephone set, together with means for mechanically locking and unlocking the switchhook of said telephone instrument, whereby its receiver may be removable for use as a radio telephone receiver, without closing the telephone circuits.

Fig. 6 is a fragmentary view of the upper portion of the desk standard equipped with a lock as shown in Fig. 5.

Referring to Figs. 1, 2, and 3 of the drawings, 1 and 2 are line wires leading from a telephone central office to the telephone subscriber's station T. At the central office end of the line suitable terminals are supposed to be provided, and a bridged source of current such as the usual battery feeding into the line through typical choke coils. The usual voltage in manual telephone exchanges

is 22. The usual voltage in automatic telephone exchanges is 50, where electromagnetic switching is relied upon, and in the present case all the circuits shown and described have been tested on voltages ranging from 22 to 50, with entire success. Unless otherwise stated, however, in this application the central office battery may be assumed to deliver from 22 to 25 volts at its terminal. It need scarcely be said that the choke coils at the central office are individual to the lines whenever the battery busses are connected thereto, these coils representing either cord circuit relay or repeating coil or choke coil units, or line relay windings normally included when the line is not in telephone use. Under all conditions, a steady flow of current not exceeding 350 milliamperes may be assumed as within good practice, over the ordinary telephone lines, including paper cables. A larger current than this can be drawn through ordinary lines up to say one half ampere, without violating the underwriters' requirements, but in such case special provision must be made for preventing operation of the ordinary "sneak-current" or heat coil arresters, which are usually set at not to exceed 350 milliamperes for a limited time. The tube V employed in the radio telephone set shown is supposed to take only 60 milliamperes in its filament circuit, and a negligible amount in its plate circuit. As a matter of fact, when the tests were made on these circuits, the best results were attained with a filament current not exceeding 50 milliamperes.

Bridged across the wires 1-2 is the telephone T, having a transmitter t, a receiver r, switchhook h, a ringer r' and a 2mf condenser C³. Extending from the telephone terminals to the radio telephone set are wires 3-4. Wire 3 goes to the head set r¹ from which wire 5 extends to the tickler coil 6 and thence to the plate p of the detector tube V. It should be stated that wire 1 goes to the positive or plus side of the central battery and wire 2 to the minus or negative side; hence the connection of the plate p of the subscriber's vacuum tube is correct, being to the positive side of battery. Wire 3 is also connected to wire 5^a through a compensating resistance r¹h to the filament rheostat of the tube V. The filament f is connected on its other side to the wire 4 and thence back through wire 4 to the No. 2 or negative side of line.

On its input side, the tube V has its grid circuit connected as usual through a grid condenser and a grid leak to the secondary coil i of the coupler coil I connected to the antenna circuit 7-8. C' is the tuning condenser for the antenna circuit, and C² the corresponding condenser for the input circuit.

65 The operation of this circuit of Fig. 1 is

as follows: through an ordinary line of approximately 1 mile to 1½ miles long, the potential available at the telephone terminals is from 18 to 20 volts, which is sufficient for the radio telephone circuits, both plate and filament, using a detector and telephone head set only. With the telephone in the position of disuse as shown in the drawing, the full voltage and full current supplied over the line are available for the radio telephone. If the telephone receiver r is taken down for use, however, during use of the radio telephone, it will be observed that a direct bridge of low resistance is put across the line by way of the wire 1^a, winding i² of the induction coil I, switchhook h, and telephone transmitter t. This draws enough current from the line to cause a decided drop in potential, which must be compensated for, especially in the filament circuit of the radio telephone. This compensation is effected through the use of a booster battery B'. 75 80 85

The circuits shown in Figures 1, 2 and 3 are only three out of a large number that might be presented in which a booster battery is the main feature. In the present case this battery maintains the voltage on both the plate and filament circuits of the radio telephone, and is normally charged from central at all times when the telephone is not in use. Also, it is possible to place a booster battery at a central point, putting it in the line, in series with the ordinary battery supply, so that for example when a line is in use for radio receiving it will have imposed upon it a total of say 50 volts, one-half of which is derived from the bridged main telephone battery, and the other half from the series booster battery included in the individual line. This booster battery 90 95 100 105 110 115 120 may feed more than one line, being provided in such case with bus bars accessible to all the lines requiring boosting and one side of each line may be opened and the ends connected to opposite bus bars of this booster battery, through choke coils as shown in Fig. 4. In such case the continuity of each line may be preserved by bridging the gap thus produced by a talking and ringing condenser of say 2mf capacity. As hereinbefore stated, the choke coils on opposite sides of these condensers, must be individual to the lines in order to prevent cross-talk through the booster battery busses. (See Fig. 4.) 125

Referring to the specific bridge booster batteries herein shown, and especially the arrangement of Fig. 1, a cut off relay R has its windings included in series with the telephone transmitter t and shunted by a condenser C⁴, so that when the telephone is in use, relay R is energized to pull in its armatures and disconnect the wires 3-4 from the line wires 1-2. Across these wires 3-4 between the radio telephone and the 130

telephone is bridged the booster battery B' , consisting of the same or approximately the same number of cells, and having the same normal voltage, as the main telephone battery at central, and connected with the same pole and the same sides of line. Normally this battery is charged from the central office, and when the cut off relay R is energized, battery B' carries the load until the telephone again goes out of use.

In Fig. 2 the same arrangement of booster battery is shown with the same radio telephone circuits and the same telephone circuits, but instead of a cut off relay, the wires 3 and 4 are connected and disconnected to and from the line wires 1-2 by means of switching terminals h' , h^2 , h^3 , h^4 , controlled by the switchhook h and when the hook is up these are open, when it is down they are closed. When the hook is up the radio telephone and booster battery are therefore cut off from the telephone line, and when the hook is down they are connected thereto.

Fig. 3 shows a modification employing the same radio circuits and battery and the same telephone, but without any cut off. In this case the battery is permanently connected across the line, through choke coils b^2 , similar to the usual choke coils at the central office. In this case when the telephone is in use, it draws a certain amount of current from the booster battery, in parallel with the main battery, each feeding through a pair of substantially identical choke coils. The booster battery however, owing to the line resistance will furnish somewhat more than one-half of the current absorbed in the telephone circuit, unless the resistance of the coils b^2 or other compensating resistance is adjusted to balance. Various arrangements for this purpose will suggest themselves to those familiar with the art. The main point is that in this case the battery B' is permanently floated on the line, and its charge and discharge currents ebb and flow according to the conditions on said line.

In Fig. 3, there can be no leakage between telephone and radio telephone, since the choke coils b^2 prevent the passage of voice current into the radio telephone currents, and the bridged battery, having a very low internal resistance, short circuits all audio currents originating in the radio telephone circuit. This is desirable where the two pieces of apparatus are permanently connected to line, although as stated before, subscribers sometimes actually prefer to hear the radio broadcasting in their telephone receiver; and if there is leakage, this also affords an opportunity for the central office operator to listen over the line.

Fig. 5 shows the same diagram as Fig. 1, with the exception that the secondary i' of a radio receiver induction coil is connected

through switch S^2 with windings of the ordinary telephone receiver r forming a part of the telephone set T . In order that the receiver r may be used to listen to radio communications without closing the telephone circuit, I provide a mechanical lock consisting of a ring or collar L (see Fig. 6) at the head of the column of the desk stand, with a notch in it normally lying over the lever of the switchhook h . In this position, the telephone receiver may be taken down for ordinary telephonic use, and an index marked l^2 on the collar then registers with a corresponding index marked l^4 , on the desk stand, marked "tel". The collar L has a handle and by means of this the collar can be rotated until the index marked l^2 registers with a second angular displaced index mark l^3 "rad." In this position of the collar L , the notch l will have passed beyond the shank of the hook h so that the latter cannot rise but is locked. Hence the receiver can be safely removed therefrom without closing the telephone circuits. The switch S^2 may be operated manually or otherwise so as to close the radio circuit and the telephone receiver when the telephone switchhook is locked and not otherwise. As a matter of fact, I have found by actual test that persons using the telephone are not seriously disturbed by receiving the radio modulations in the same receiver, unless the latter are amplified so as to be very loud. The switch S^2 may cut in a regular headset when the telephone is in use, if desired, but in practice it is thought this switch will be best regulated by the subscriber himself.

What I claim is:

1. In a combined telephone system and radio telephone system, a pair of line wires, a central office source of current supply for said line wires, a subscriber's telephone of relatively low resistance connected across said line wires, a subscriber's radio telephone of relatively high resistance also connected across said line wires, means for supplying current from said central source at a fixed voltage to either or both of said instruments over the line wires and a booster source of current arranged to supply extra energy to the radio instrument to compensate for the drop in voltage when the telephone instrument is put in use simultaneously therewith.

2. In a combined telephone system and radio telephone system, a pair of line wires, a central office source of current supply for said line wires, a subscriber's telephone of relatively low resistance connected across said line wires, a subscriber's radio telephone of relatively high resistance also connected across said line wires, means for supplying current from said central source at a fixed voltage to either or both of said instruments over the line wires, and a booster battery normally bridged across the radio

telephone terminals and adapted to maintain required voltage thereon and required current supply therefor when the telephone is in use.

5. 3. The system claimed in claim 2 with means operable automatically upon use of the telephone to disconnect the booster battery from the line while maintaining it connected across the radio telephone terminals.

10 4. The system claimed in claim 2 with a relay energized in series with the telephone circuit and operable upon energization to open the line circuit between the radio tele-

phone and the telephone, leaving the booster battery connected to the radio telephone terminals.

5. The system claimed in claim 2 with a switch controlling the telephone circuit and provided with contacts arranged to open the line circuit between the radio telephone and the telephone upon raising of the switch-hook of the latter.

In testimony whereof I hereunto affix my signature.

EDWARD E. CLEMENT.
